(57) **CLAIM**

The ornamental design for a front baby carrier, as shown and described.

DESCRIPTION

FIG. 1 is a left side elevational view of a front baby carrier, having a top flap portion extending upwards and showing the new design in use.

FIG. 2 is a front elevational view of FIG. 1;

FIG. 3 is a left side elevational view thereof;

FIG. 4 is a right side elevational view thereof;

FIG. 5 is a front elevational view thereof;

FIG. 6 is a left front perspective view thereof;

FIG. 7 is a left side elevational view thereof showing the front baby carrier in use, having the top flap portion folded down and the baby facing forward in the carrier.

FIG. 8 is a front elevational view of FIG. 7; and,

FIG. 9 is a rear perspective view of the design of FIGS. 1 through 8.

The patterns in the views are understood to be continuous throughout the surfaces to which they are applied.

The broken lines in FIGS. 1-2 and 7-9 depict environmental elements to show the appearance of the design in use and form no part of the claimed design.
